METAL ROOFING

Filed Sept. 19, 1947

UNITED STATES PATENT OFFICE

2,538,481

METAL ROOFING

Jay W. Stoltz, Eucyrus, Ohio

Application September 19, 1947, Serial No. 775,013

5 Claims. (Cl. 108—21)

1

This invention relates to an improved metal roofing.

It is an object of this invention to provide an improved metal roofing formed of a flat metal sheet so related to an adjacent sheet and to the roof to which it is attached that the roofing will be securely fastened to the structure and the adjacent sections will be leak proof.

Another object of this invention is to provide an improved metal roofing formed of adjacent metal sections secured together by an improved resilient clamp for sealing the engagement of the adjacent sections.

A further object of this invention is to provide an improved metal roofing of the kind to be more particularly described hereinafter in which the adjacent roofing sections may be sealingly secured together, and having means for securing the connected sections to the supporting or roof structure whereby the entire roofing will be held against removal by wind or storms or the like.

With the above and other objects in view, my invention consists in the arrangement, combination and details of construction disclosed in the drawings and specification, and then more particularly pointed out in the appended claims.

In the drawings,

Figure 1 is a top plan view partly broken away, of an improved metal roofing constructed according to an embodiment of this invention,

Figure 2 is a horizontal section taken on the line 2—2 of Figure 1,

Figure 3 is a vertical section taken on the line 3—3 of Figure 2,

Figure 4 is a vertical section taken on the line 4—4 of Figure 2, and

Figure 5 is a horizontal section taken on the line 5—5 of Figure 2.

Referring to the drawings, the numeral 10 designates generally a flat sheet of metal forming a section of a metal roofing which is adapted to be secured to the rafters 11 or supporting structure so that the roofing will be securely attached to the structure and held against inadvertent removal by wind or storms or the like.

The flat section 10 is formed of a central flat body portion 12 having a peripheral flange 14 formed along the edge thereof. The flange 14 extends vertically upwardly from the panel or central section 12 at right angles thereto.

The flange 14 extends along one longitudinal edge of the central panel 12 and is adapted for engagement with a flange 15 of an adjacent panel 16 or roofing section 10—a.

The flange 15 is formed of a vertically extend-

2

ing arm 17 perpendicular to the base 16 having a reverted arm 18 extending downwardly from the upper end thereof. The flange 14 of the panel 12 is adapted to engage between the arms 17 and 18 of the flange 15 on the adjacent section 10—a.

The panels 12 and 16 may be secured to the rafters 11 by bolts 19 which engage through the body of the panels and into the rafters. For sealing the engagement of the flanges 14 and 15, I have provided a spring pressed metal clamp 20. The metal clamp 20 is formed of a clamping member 21 which is adapted to engage one of the flanges as 15 along the length thereof.

The clamping member 21 is formed with an upper flat end 22 which is adapted to overlie in abutting relation the upper end of the arm 17. The lower end of the clamping member 21 is bowed outwardly as indicated by the numeral 24 so that the lower end of the member 21 is resiliently biased toward the flange 15 at the lower edge thereof.

A horizontal arm 25 is fixed to or formed on the upper end of the clamping member 20 to overlie the upper edge of the flanges 14 and 15. A similar clamping member 26 is provided for abutting engagement along the length of the flange 14. The clamping member 26 is formed of a flat upper section 27 extending along the length of the flanges substantially parallel thereto and formed with a lower end 28 arcuate in configuration opposite to the arcuate lower end 24 for clamping the flanges 14 and 15 between the lower ends thereof.

The upper edge of the clamping member 26 is adapted to underlie the horizontal member 25 of the clamping member 20. The horizontal arm 25 provides a suitable seal between the clamping members 20 and 26 to exclude rain or other moisture from between the flanges 14 and 15.

For securing the connection of the adjacent roofing sections 10 and 10—a together, an elongated bolt 29 is provided. The bolt 29 is formed with a head 30 on the upper end thereof and is adapted to engage between the flanges 14 and 15 and between the clamping members 20 and 26.

For sealing the engagement of the head 30 of the bolt 29 with the upper edge of the flanges, there is provided a U-shaped cap 31. The bight 32 of the cap 31 is adapted to overlie the arm 25 of the clamping member 20 and the arms 33 which extend downwardly from the bight 32 abuttingly engage the parallel side portions 21 and 27 of the clamping members.

In the use of the bolt 29 for attaching the roofing sections to a rafter 11, provision in the flanges

need not be made for the bolt as the engagement of the bolt therebetween will force the flanges outwardly to a suitable contour as indicated in Figure 5 to permit the engagement of the bolt therebetween.

In Fig. 4 I have shown a means for attaching the entire assembly to the rafter 11. An attaching strip 40 is provided for engagement with both of the flanges 14 and 15. The attaching member 40 is formed of an elongated length of flat narrow material forming a lower horizontal arm 41 for attachment to the rafter 11.

An upper or vertically extending arm 42 is formed at one end of the arm 41 and is adapted to be disposed between the flanges 14 and 15. The arm 42 at its upper end is reverted to form a depending vertical arm 44. The arm 44 is adapted to engage between the outer surface of the flange 14 and the inner surface of the depending arm 18 on the flange 15.

The vertical arm 42 is again reverted at the lower end of the arm 44 to provide a vertically extending arm 45 outwardly of the arm 18.

The arm 45 follows the contour of the arm 18 upwardly and is bent over the upper end of the flange 15 to provide a downwardly extending arm 46 overlying the outer edge of the vertical portion 17. The attaching member 40 may be disposed at suitable spaced apart positions along the length of the flanges 14 and 15 for attaching them to the rafters 11, and is normally contained between the clamping members 20 and 26.

A horizontal bolt 47 is provided for engagement through the clamping members, the attaching member 40, and the flanges of the adjacent roofing sections for securing them together. The resiliency of the clamping members 20 and 26 is determined by the tension on the bolt 47 effected by the nut 48 threadably engaged thereon.

I do not mean to confine myself to the exact details of construction herein disclosed but claim all variations falling within the purview of the appended claims.

Having thus described my invention, what I claim is:

1. A metal roofing comprising an elongated flat sheet of metal, a vertical flange on one longitudinal edge of said sheet, a reverted vertical flange on the opposite longitudinal edge of said sheet, said first flange slidably engaging within the reverted vertical flange of an adjacent sheet, a pair of resilient bowed clamping members engaging about said engaged flanges and means securing said clamping members to said engaged flanges.

2. In a metal roofing a pair of elongated flat metal sheets, a vertical flange on one of said

sheets longitudinally thereof, a reverted vertical flange on the other of said sheets, said first flange engaging between the reverted portions of said latter flange, a pair of resilient clamping members about said engaged flanges along the length thereof and means engageable through said flanges and said clamping members securing said members on said flanges.

3. A metal roofing comprising a pair of flat metal sheets, inter-engaging vertical flanges on the adjacent longitudinal edges of said sheets, a pair of opposed resilient clamping members disposed along the length of said flanges on opposite sides thereof, a horizontal flange on one of said clamping members overlying the upper edge of said inter-engaged flanges and the upper end of the other clamping member for sealing said flanges at their upper edges, and means securing said clamping members to said inter-engaging flanges.

4. A metal roofing comprising a pair of flat metal sheets, inter-engaging vertical flanges on the adjacent longitudinal edges of said sheets, a pair of opposed resilient clamping members disposed along the length of said flanges on opposite sides thereof, a horizontal flange on one of said clamping members overlying the upper edge of said inter-engaged flanges and the upper end of the other clamping member for sealing the said flanges at their upper edges, means engaging about said clamping members and extending downwardly between said flanges for securing said sheets to a roof, and means securing said clamping members to said inter-engaging flanges.

5. In a metal roofing having a pair of flat metal sheets including marginal vertical flanges, a clamping means securing said sheets together along a marginal edge comprising a pair of clamping members engageable on opposite sides of adjacent flanges, each of said members including a lower outwardly bowed resilient clamping jaw, an attaching plate connected to each of said jaws, a horizontal flange on one of said attaching plates overlying said adjacent flanges and means extending through said plates and said adjacent flanges for clamping said flanges between said jaws.

JAY W. STOLTZ.
